K. KOHN

SAFETY TORPEDO

Filed July 31, 1926

FIG. 6.

Inventor
Kohy Kohn,
by Watson, Coit, Morse & Grindley

Attorney

UNITED STATES PATENT OFFICE.

KOBY KOHN, OF NEW YORK, N. Y.

SAFETY TORPEDO.

Application filed July 31, 1926. Serial No. 126,184.

This invention relates to toy torpedoes and more particularly to what may be termed safety torpedoes in which, until the time of impact, there are no movable abrasive or detonating elements.

It is a general object of the present invention to provide a novel and improved type of toy torpedo.

More particularly it is an object of the invention to provide a toy torpedo, having a container for explosive, and means to initiate the explosion of said explosive only upon intentional or severe impact of the torpedo against a hard surface.

Another object of the invention consists in the provision of a receptacle or container for the explosive material of a toy torpedo, said receptacle being formed of a frangible moldable material and having a recess for the reception of the explosive and a striker projecting into the recess from one of the walls thereof and adapted to be broken loose to strike the walls when the torpedo is subjected to a sudden impact.

A further object of the invention consists in the provision of a toy torpedo in which the container for the explosive is formed of a moldable and frangible material having incorporated therein small particles of a heavy material to impart additional weight and abrasive action to portions of the container when they are broken off to initiate the explosion.

Other and further objects of the invention will be more apparent to those skilled in the art after a consideration of the accompanying drawings and following specification wherein are disclosed several exemplary embodiments of the invention with the understanding, however, that various changes may be made therein without departing from the spirit of the invention or the scope of the appended claims.

In said drawings:

Figure 1 is a section thru a spherical form of torpedo taken thru the axis of the recess;

Figure 2 is a similar view of a tube type of torpedo;

Figure 3 is a horizontal section on line 3-3 of Figure 2;

Figure 4 is a central section thru a modified form of a torpedo in which the striker is secured to the closure;

Figure 5 is a view similar to Figure 1 but showing the use of weighted material for forming the explosive container;

Figure 6 is a view similar to Figure 1 showing the use of a weighted material for the explosive container and the use of abrasive on the walls of the recess and the striker; and

Figure 7 is a section of a torpedo of the type disclosed in Figure 1 immediately following its impact on a hard surface.

Toy torpedoes, as usually manufactured at present, comprise a container or receptacle generally made of paper, pasteboard or the like in the form of a tube with closed ends or in the form of two telescoping cups. Into such container is placed an explosive composition, in powdered form, and some abrasive or detonating means such as gravel or the like. This gravel, as it will hereinafter be called, is loosely placed in the container and thus offers a considerable hazard, in that slight tremors and jars may cause sufficient movement of the particles of gravel to produce sufficient heat by friction to ignite the explosive material which is scattered over the surface of the gravel. In order to overcome such difficulties attempts have been made to reduce the sensitivity of the explosive material but that often requires that too great an impact be given the torpedo when it is to be intentionally fired. This results in misfires if the torpedo is not thrown hard enough and generally makes an unsatisfactory torpedo. The present invention provides a type of torpedo in which there is no loose or movable abrasive or detonating means and in which may be used an explosive material of extreme sensitivity without any danger of accidental detonation. The result is attained by having the detonating medium frangibly secured to a wall of the container so that it is held rigid and relatively immovable in respect to the container until an impact of the container against a hard surface causes the momentum of this detonating medium to break it loose from

the container.

- its supporting wall and move it into contact with one of the walls of the container thus abrading or detonating the explosive which covers it and the walls of the container.
- 5 Referring to the drawing, there is disclosed at 10 a cup-like container for the explosive material. It is in the particular form shown in Figure 1 substantially spherical and provided with a recess 11 which is frustro-conical, the larger base of the cone being at the open end. This particular form of recess is provided in order to give draft to the mold. From the bottom or smaller base of the conical recess, or in fact from any one 10 of the walls of the same, there projects what may be termed a striker 12. The recess at the bottom or junction of the striker with the base thereof is narrowed into a V-shape as shown at 13 and extends almost to the 15 surface of the sphere leaving only the narrow ring 14 of material to retain the striker in position. A cap 15 closes the opening of the recess and completes the spherical configuration of the container. The explosive material 16 is placed in the container 20 between the walls 17 of the recess and the striker 12 before the cap 15 is positioned and sealed in place to make a gas tight and moisture proof enclosure for the explosive.
- 25 The material of which the container is formed is preferably a plastic or mastic which is readily moldable either by the use of heat to soften the same or by the use of some solvent which readily evaporates to cause hardening. A composition such as 30 disclosed in my copending application, Serial No. 45,657, filed July 23, 1925, may be used altho this is not necessary. In general it is preferred to use a composition of 35 high melting-point pitch, a binder of some sort such as shredded asbestos and a filler of inert material such as fuller's earth, kieselguhr or the like. The casing or container when hardened is relatively frangible so that 40 upon impact it is broken into a number of small pieces. The material from which the container and the cap 15 are formed can readily be molded in metal molds to the 45 form disclosed and large numbers of the containers can be made simultaneously and at an extremely low cost.
- 50 Around the exterior of the container is placed a gas tight resilient medium 18. This medium may be glue or a similar material which is originally in a liquid state in 55 which the cups after filling may be dipped and the material allowed to harden. Preferably it should not stick to the exterior of the container. If the container is formed 60 of a pitch composition this condition is readily met for the oily surface of the pitch offers resistance to adhesion from ordinary water soluble adhesive.
- 65 When a torpedo constructed as just described is thrown against a hard surface, the casing and its envelope are brought to a sudden stop but the momentum of the striker 12 causes it to continue to move and in so doing it is broken loose from the remaining portion of the cup at the thin section 14. Continued movement of the striker causes it to impact against one of the inner walls of the container and abrade or otherwise initiate the explosion of the material 16 contained therein. A consideration of Figure 7 70 will indicate the condition of the torpedo at the moment of impact on a hard surface such as 19. It will be seen that not only has the striker broken loose from the remaining portion of the container but that 75 part of the container in immediate contact with the surface 19 has been broken to some extent. This condition may or may not prevail, dependent upon the severity of the impact. It has been found by careful tests 80 that the position of striking is immaterial and that the striker will be broken loose under all conditions and will impact with the sides of the cup with sufficient energy to initiate the explosion. The envelope 18, being 85 resilient and not adhering to the material of the container, remains gas tight in order that its disruption by the expanding gas will cause a loud report.
- 90 It may sometimes be found that the material of the container is not sufficiently hard or abrasive to cause the explosion and therefore, as shown in Figure 1, it may be well, in order to insure a high percentage of explosions, to line the walls 17 of the container 95 and the outer surface of the striker 12 with abrasive material 17' such as small mesh sand, emery or the like which may be caused to adhere to these surfaces in any desired manner. Where the mastic composition is 100 softened by heat, the abrasive may be heated and poured into the recess 11 and that abrasive which is in engagement with the walls 105 will sufficiently soften them to adhere thereto and the remainder may be poured out.
- 110 In Figure 2 is shown a torpedo of the tube type. Its details of construction are substantially identical with those of the torpedo shown in Figure 1 the only difference 115 being in the exterior configuration and in the relative shapes of the parts. In this form the striker 20 is thinner and longer and for this reason may sometimes break in several parts in addition to separating from the container, thus increasing the certainty of exploding. In this form as well as in the other form the closure caps 15 and 21 are 120 preferably formed of the same material as the container and may be secured thereto by the use of a suitable adhesive or solvent or by slightly heating either the edges of the closure or the edges of the opening of the container and pressing the closure in position. Obviously a large number of the closures may be applied simultaneously if de-

sired. The material from which the containers are formed is practically blown to bits as a result of the explosion and no large particles are therefore thrown to any great distance, thus adding an element of safety to bystanders.

In Figure 4 is shown a torpedo which may have any desired external configuration and any desired shape of recess within reason. The cup 22 is formed with walls of any desired thickness and with an opening at the top having flaring walls 23. The striker 24 in this instance is carried by the closure cap 25 having such a configuration as to readily fit against the walls 23 and be secured thereto. A channel or groove 26 is formed around the bottom of the striker to increase the frangibility so that the striker may be broken loose as in the case of the previously described forms. This form offers great ease of manufacture for the abrasive may be readily applied both to the interior of the cup and the exterior of the striker.

It is sometimes found desirable to weight the striker in order to increase its momentum and striking energy. This may best be done by mixing a heavy material with the plastic composition. It may sometimes be advisable to use, as the weighting material, an abrasive so that none need be applied after the molding process. In the form shown in Figure 5 it will be seen that the container is identical with that disclosed in Figure 1 but has incorporated in the material of the container the particles 27 to increase the weight. These particles may be sand, gravel or other abrasive or may conveniently be iron filings or small metal chips. Those which stick thru the surface increase the abrasive qualities of the walls of the recess and the surface of the striker in addition to augmenting the weight of the striker. The closure 28 need not be provided with the weighting or abrading material altho it may be if so desired.

Sometimes it may be found desirable to provide not only the weighting material but also the abrasive lining for the container. This feature is shown in Figure 6 in which is disclosed at 29 suitable weighting material such as metal filings or shavings incorporated in the plastic mass from which the container is molded. At 30 are disclosed particles or granules of abrasive material such as that previously mentioned secured to the inner walls of the container and to the surface of the striker.

It will be understood from the above that the primary intent of the present type of torpedo is to provide safety during manufacturing, shipping and storing of the torpedo and this is done by providing a cup, which acts as a container for the detonating material, which when it is desired to intentionally explode it, is transformed by the im-

pact into elements for abrading, detonating or otherwise initiating the explosion of the explosive material. These transformed elements formed from the breaking of the cup parts act in the same capacity as the gravel now used in other types of torpedoes.

Having thus described the invention, what is claimed as new and desired to be secured by Letters Patent is:

1. As a new article of manufacture, a container for a toy torpedo having a recess therein and a projection frangibly secured to said container and within said recess. 75

2. As a new article of manufacture, a frangible container for a toy torpedo having a recess therein and a projection secured to said container and within said recess. 80

3. As a new article of manufacture, a frangible container for a toy torpedo having a recess therein and a projection integral 85 with said container and extending within said recess.

4. A toy torpedo including in combination, a completely enveloping container for an explosive, means adapted to cooperate 90 with the interior of said container to initiate the explosion of said explosive, said means being frangibly attached to said container.

5. A toy torpedo including in combination, a cup-like container for an explosive, a closure for said container, means in said container secured to a wall thereof and normally out of contact with the remaining walls to set off the explosive in said container upon sufficient impact of the torpedo to break said means from its walls. 95

6. A container for explosive for a toy torpedo comprising a frangible mass having a recess therein, a cover to close the opening 100 of said recess to the exterior of said mass and a striking element projecting into said recess. 105

7. A container for explosive for a toy torpedo comprising a frangible mass having a recess therein, a cover to close the opening 110 of said recess to the exterior of said mass and a weighted element projecting into said recess.

8. A cup-like container for explosive for a toy torpedo having a deep recess therein, a cover to close said recess, an elongated projection extending into said recess and having a frangible support adapted to be broken by the momentum of said projection when the torpedo is impacted. 115

9. In a toy torpedo in combination, a cup portion, a closure portion therefor, a projecting striker extending into the recess of said cup and being frangibly supported from one of the portions, said striker having an abrasive surface and being large in respect to said recess. 125

10. In a toy torpedo in combination, a cup portion, a closure portion therefor, a projecting striker extending into the recess of 130

said cup and being frangibly supported from one of the portions, said striker and cup recess walls having abrasive surfaces.

11. In a toy torpedo in combination, a completely enveloping container for explosive, a striker within said container and stationary in respect thereto, said striker being adapted to move in respect to said container when the torpedo is impacted.

10 12. In a toy torpedo, in combination, a gas tight molded container having a recess therein forming a compartment for explosive, a substantially conical member extending into said recess, said member being connected with a portion of said container by frangible means.

13. In a toy torpedo, in combination, a molded container having a deep recess therein forming a compartment for explosive, a

20 cover to seal said compartment, a striker member extending into said recess from a wall thereof, said wall surrounding the area of attachment of said striker being thin and frangible.

25 14. In a toy torpedo, in combination, a gas tight container for the explosive, said container being formed from a molded weighted plastic material.

15. In a toy torpedo, in combination, a 30 container for the explosive formed of a weighted moldable material and a non-adhering gas tight covering.

35 16. In a toy torpedo, in combination, a cup portion, a closure portion therefor, a projecting striker extending into the recess of said cup and being frangibly supported from one of the portions, said striker being weighted and having an abrasive surface.

17. In a toy torpedo, in combination, a gas tight frangible container having an 40 inner compartment, explosive in said compartment, a striker projecting integrally from an inner wall of said compartment, said striker being weighted and said striker and the walls of said compartment having 45 an abrasive coating.

18. In a toy torpedo, in combination, a cup-like member having a frustro-conical recess therein, a substantially frustro-conical striker member projecting into said recess from the smaller base of said frustum, said cup and striker being molded integral from a mastic, abrasive on the walls of said recess and surface of said striker, explosive in said recess surrounding said striker, a closure for 55 said recess and a gas tight resilient covering surrounding said cup.

19. In a toy torpedo, in combination, a closed container, an explosive composition in said container and a normally stationary 60 member projecting into said container and adapted, when the torpedo is impacted, to engage the explosive between the member and a wall of the container to explode the same.

20. As a new article of manufacture, a container forming a gastight enclosure for explosive for a toy torpedo, said container having means secured to an inner wall and adapted to leave said wall to detonate the 70 explosive in said container when the torpedo is impacted.

In testimony whereof I hereunto affix my signature.

KOBY KOHN.
